ADJUSTABLE PAINT STRIPING DEVICE

Karl V. Eklov, Detroit, Mich.

Application July 29, 1932, Serial No. 625,741

4 Claims. (Cl. 91—62.6)

My device relates to an adjustable paint striping device, and is a modification of my former paint striper shown and described in my former patent application Serial No. 484,283, filed Sept. 5, 1932, and the special striping nib herein illustrated is more fully set forth in detail in said former application. The improvements herein shown and claimed are applicable to any other type of tubular paint striping unit equally as well, although I have chosen to illustrate it as applied to the specific nib as set forth in the former patent application.

The object of my invention is to produce an adjustable paint striping device that is adapted for following any irregular guide strip and operate in various positions thereon.

Another object is to produce a paint striping device that is interchangeable on position and can be reversed to operate in different directions.

20 A further object is to produce an adjustable paint striper having a swiveled paint container capable of being retainer in a vertical position regardless of the position of the striping nib.

25 A still further object is to produce an adjustable guide means for a paint striping device that will retain the marking unit in any predetermined position along a painted wall, and with the guide members adjustable to various positions thereon.

30 These several objects are attained in the preferred form by the construction and arrangement of parts more fully hereinafter set forth.

Similar parts on all drawings are marked by similar numerals or letters.

35 Fig. 1 shows a side view of my device and the general arrangement of the connected operating parts.

Fig. 2 is a top view of the striper showing the relative position of the liquid paint container and other operating units.

40 Fig. 3 is a bottom view of the striper showing the double guide arms as mounted thereon.

Fig. 4 is an end view taken on the line 4—4 of Fig. 1 showing the relative positions of the guide points to the paint striping nib.

45 Fig. 5 is an end view taken on the line 5—5 of Fig. 1 showing the casing structure and release means.

Fig. 6 is vertical sectional view taken lengthwise of the device along line 6—6 of Fig. 2, showing the interior arrangement of the operating parts.

50 Fig. 7 is a partial sectional view taken on the same line 6—6 of Fig. 2, where the casing only is cut leaving the operating units in full, show-

ing the striping nib and connected paint container in its recessed position, required before the nib can be rotated within the inclosing casing.

Fig. 8 is a cross sectional view taken on the line 8—8 of Fig. 6 showing paint container and means for rotatably mounting same on the nib collar.

Fig. 9 is also a sectional view taken on the line 9—9 of Fig. 6 showing the adjustable guide 10 arm frame and the casing recess for retaining the various units in predetermined positions therein.

Fig. 10 is an enlarged detail view of the marking disc as mounted in the end of the paint striping nib, showing the spring adjusting means.

Fig. 11 is an edge view of the marking disc shown in Fig. 10, showing the pinned surface formed thereon.

In general, my device comprises a tubular paint striping nib, of any chosen design, slidably mounted within a tubular casing member, and held in position by a spring member mounted therein, said tubular nib being rotatable to various positions within the casing. The striper 25 nib carries rotatably mounted thereon a swiveled paint container connected to the striper nib point by an intervening channel passage and opening therein at all positions. An adjustable guide block with adjustable guide arms is slidably mounted on the tubular casing end and positioned to surround the nib point in all of its various positions.

I will now describe more fully the detailed construction of my device referring to the drawings and the marks thereon.

The nib 1 is more fully described in my former patent application referred to, Serial No. 484,283, filed Sept. 25, 1930, and comprises a tubular body 2 flattened at the outer end point and is formed 40 with a central liquid passage 3 lengthwise therethrough and terminating in a cylindrical chamber 4 at the outer nib point. The chamber 4 carries rotatably mounted therein a pinned surface striping wheel 5 partially surrounded by a spring disc shield 6, said shield being designed to regulate the flow of paint therethrough. A small adjusting screw 7 is mounted in the nib point for adjusting the spring end to the pinned surface of the wheel. The inner end of the 50 nib 1 is formed with a cylindrical end collar 8 provided with paint groove and ports 9 and 10 which leads directly into the paint passage channel 3. A small liquid paint container 11 formed with a cylindrical end bearing 12 is rotatably 55

- mounted on the inner end collar *g* of the striping nib *l* and is retained thereon by the end collar *p* screwed within the inner end of the liquid channel *b*. The paint container *m* is preferably positioned at an angle leaning back from the nib point and is rotatable thereon to any position about the collar end. The container *m* opens directly into the collar groove and ports *h* and *k* providing a clear passage from said container to the nib point for all positions of said container. A small airport *q* is formed through the container cover *r* and may be closed by the disc *s* pivotally attached thereto.
- The cylindrical paint striping nib *l* is slidably mounted within the shouldered end *t* of the tubular casing *2*, said tubular end preferably being formed by inserting the smaller tube section *t* within the casing end and fixedly attaching the same thereto by welding. A guide pin *3* is fixedly mounted on the top side of the cylindrical striping nib *l*, and is positioned therein to engage the recess slots *4* and *5* formed in the top and bottom walls of the casing end *t*, positioned diametrically opposite each other, and retains the striping wheel *d* in a plane at right angles thereto. The nib *l* is firmly held in its extreme end position as shown in Fig. 1 of the drawings by a coil spring *6* mounted within the handle end of the casing *2*. An adjusting operating rod *7* is fixedly attached to the threaded plug collar *p* of the nib *l*, or made a part thereof, and is extended aximetrically through the casing *2* and projected out through the casing end cap *8*, providing means for withdrawing the nib *l* within the casing end *t* and reversing the nib position and changing position of the guide pin *3* in the wall slots *4* and *5*. By reversing the position of the nib *l* within the casing, the striping wheel *d* is also reversed in position and the striping may be operated in the opposite direction. As the nib *l* is rotated within the casing *2*, it also rotates within the bearing *n* of the paint container *m*, and at the same time the container *m* may be rotated from one side of the casing to the other through the casing wall slot *9* as indicated by the dotted positions *m'* of Fig. 8 of the drawings. The wall slot *9* is formed of sufficient length to allow the withdrawal of the assembled unit for changing position and adjusting the nib *l* to either of the wall slots *4* or *5* for changing position of the striping wheel *d*. In using the striping device along irregular lines of travel such as turning from a horizontal to a vertical direction, the container *m* may be rotated from one side to the other through the casing slot *9* by the user, for retaining the container in as nearly a vertical position as possible, assuring constant pressure and flow of the liquid paint through the striping nib as possible. Likewise the tilting of the container *m* at an angle back from the nib point allows the paint to flow therethrough even though the striping is applied to a painted surface in a vertical position as when striping on a flat level surface.
- Mounted over the shouldered end *t* of the casing is a rectangular guide block *10*, said block being formed with a centrally positioned cylindrical opening therethrough which fits and slides over the tubular end section *t*, and is positioned thereon at right angles to the plane of the striping wheel *d* of nib *l*. The block *10* is retained fixedly thereon by a small thumb screw *11* engaging one of the parallel wall slots *12* formed in the casing tubular end, said slots *12* being preferably positioned on opposite sides of the tubular section

t and in a plane through the center of the striping wheel *d*. Along opposite edges of the rectangular guide block *10* and at right angles to the surface of wheel *d*, are formed parallel slot grooves *13* which extend the full length of the block walls. Within the slotted grooves *13* is fitted a U-shaped guide arm yoke *14* slidably mounted therein, said yoke being held in various chosen positions therein by a headed lock bolt and nut *15* and *16*, said bolt *15* being positioned through the guide block *10* adjacent the edges of the yoke *14* and tightly clamped thereon by the threaded nut *16*. It is desirable to form the grooves *13* adjacent one of the side faces of the guide block so that by reversing the position of block *10* on the supporting casing end *t*, a further longitudinal adjustment may be secured. Along the bottom bar *v* of the yoke *14* are mounted guide arms *17*, fixedly attached thereto and extended to a position in front of the casing end *t* and wheel *d*, on the outer ends of the guide arms *17* are tips bearing balls *w* rotatably mounted therein similarly to that of an ordinary ball caster, said ball *w* being retained in the arm end by the spherical casing wall *x* and supported on a small bearing ball *y* mounted within the casing base, thus allowing free rotation of the ball *w* in every direction. The position of the guide arms *17* may be adjusted along a line at right angles to the surface of wheel *d* by sliding the supporting yoke *14* along the grooves *13*. Also at the top of the guide block *10* opposite the guide arms *17* is mounted a single adjustable guide arm *18* and which is slidably mounted through an opening formed in the guide block wall and positioned parallel to the casing axis. The arm *19* is formed with an end ball tip similar to that of the arms *17* and is fixedly retained in the block recess *z* by a small thumb screw *20* tightly screwed therein. The arm *19* may be adjusted longitudinally to any desired position for engaging with any surface or guide rib formed thereon, for assisting the user in retaining the striping wheel in the required position along the line to be traced.

Inasmuch as the striping wheel *d* is operative in one direction only due to the inclosing adjustable spring shield *e* and regulating screw used therewith, it becomes necessary to reverse the position of the nib *l* within the casing *2* when it is desired to operate the striping in the opposite direction, and to accomplish this the nib *l* is withdrawn within the casing *2* against the compression spring *6* by the connected operating rod *7*, until the guide pin *3* is free from either recess *4* or *5*, and which allows the nib to be rotated within the casing to its opposite position and re-entered in the opposite recess. The striping is then ready for use in the reverse direction. The receding adjustment of the nib against the spring *6* allows for irregular surfaces and variations therefrom even though the guide arms travel a uniform path along the guiding surface.

It is apparent that my device is subject to various modifications in both design and structure and without departing from the spirit of my invention, and also that my device is applicable to use with various types of paint striping nibs, and I claim as my invention the device herein illustrated and any other structure that may be substantially a substitution of parts herein shown.

Having fully described my adjustable paint striping device, what I claim as my invention and desire to secure by Letters Patent is;

1. An adjustable paint striping device, com-

prising a tubular casing member, a cylindrical plug paint striping nib having a rotatably mounted marking disc slidably and rotatably mounted within one open casing end, said casing and nib being provided with pin and slot means for retaining the nib in various pre-determined positions within the casing end, spring means mounted within the casing for engaging the nib and retaining the same in some of its various end positions, a paint container mounted on said casing and rotatably connected to the striping nib in a manner capable of flowing liquid paint therethrough for all positions of said nib within the casing, and adjustable guide arms slidably mounted on the casing end positioned on opposite sides of the striping nib point.

2. An adjustable paint striping device, comprising a tubular casing member closed at one end, a cylindrical plug paint striping nib slidably and rotatably mounted within the opposite open casing end, said casing end and nib being formed and provided with pin and slot means for retaining the nib in various pre-determined positions within the casing end, spring means mounted within the closed casing end for engaging and retaining said striping nib in its various end positions, a paint container mounted thereon and rotatably connected to the striping nib end in a manner capable of flowing liquid paint therethrough for all positions of the nib within the casing end, means mounted within the casing for engaging the striping nib for withdrawing and changing its positions within the casing end against the spring reaction, a guide block slidably mounted on the casing open end and splined thereto and capable of adjustment lengthwise thereof, and guide arms slidably mounted in said guide block positioned therein on opposite sides of the striping nib point.

3. An adjustable paint striping device adapted for striping fine paint lines on painted surfaces, comprising a tubular casing member closed at one end and open at the opposite end and formed with parallel guide grooves at the open end, said casing also being formed with a recess opening along the top sides thereof, a cylindrical plug

paint striping nib having a paint channel therethrough and formed with a shouldered plug end having groove and port passages leading therethrough to said plug nib paint channel, said striping nib being slidably and rotatably mounted within the casing open end, a guide pin mounted in the nib wall for engaging the casing guide grooves and retaining said nib in various pre-determined positions within the casing, a coil spring mounted within the closed casing end and extended to engage the nib plug for retaining same in its various end positions within the casing, an operating rod slidably mounted through the casing end and connected to said nib for withdrawing and changing the nib positions within the casing, a paint container rotatably mounted on the inner end of the cylindrical plug striping nib and opening directly into groove and port passages formed therein, capable of flowing liquid paint through said nib for all of its positions within the inclosing tubular casing, said paint container being positioned at an angle with the casing axis, a reversible guide block slidably mounted over the open casing end and splined thereto and capable of adjustment lengthwise thereof, and adjustable guide arms slidably mounted on said guide block, said guide arms being positioned on opposite sides of the striping nib point.

4. An adjustable paint striping nib adapted for use within a paint striping device and used in combination therewith, comprising a cylindrical plug paint striping unit, having a liquid passage leading therethrough and provided with a rotatably mounted marking disc at the outer end thereof, said unit being formed with an inner shouldered cylindrical end positioned concentric with the nib plug axis, said nib shouldered end being provided with a centrally positioned annular groove and port passages leading therefrom to the striping nib passage, a paint container rotatably mounted on said nib shouldered end and positioned to open directly into the said groove and port passages formed therein and in a manner capable of flowing liquid paint therethrough for all positions of the container on said nib.

KARL V. EKLOV.
